CEILING HANGER

Filed May 19, 1927

UNITED STATES PATENT OFFICE

EUGENE T. McCARTY, OF CHICAGO, ILLINOIS

CEILING HANGER

Application filed May 19, 1927. Serial No. 192,529.

This invention relates to an improved method of hanging ceilings by means of improved brackets or hangers adapted to be set at spaced intervals in the ceiling beam forms in such a manner that after the concrete has been poured into the beam forms parts of said hangers will be imbedded in the concrete in such a manner that after the forms have been removed portions of the hanger are exposed permitting the same to be bent into a suspended position ready to receive and support ceiling supporting bars or the like in a convenient position ready to have expanded ceiling laths secured thereto.

15 It is an object of this invention to provide an improved method for hanging ceilings by means of brackets adapted to be partially imbedded in concrete ceiling beams with flanged apertured portions of said brackets exposed to permit the same to be bent downwardly to form supports for receiving ceiling bars.

It is also an object of this invention to provide an improved ceiling hanger constructed of sheet metal or other suitable material employing a toothed or irregular supporting plate having formed thereon an apertured angle plate adapted to be bent into the plane of the supporting plate after the hanger has been mounted in place.

30 It is a further object of this invention to provide a ceiling hanger adapted to be seated within a ceiling beam form and partially imbedded in concrete in such a manner that a portion of the hanger may be bent into a position to support a ceiling carrying bar to which ceiling laths or the like may be secured.

It is an important object of this invention to provide a simple and inexpensive type of improved ceiling hanger constructed of sheet metal adapted to be readily mounted in a ceiling beam form with a flanged portion of said hanger projected into a recess in the form, permitting an intermediate portion of the hanger to be so positioned that when the beam forms are removed the intermediate portion of the hanger may be bent into substantially a vertical position permitting a ceiling supporting bar to be supported on said hanger.

35 Other and further important objects of

this invention will be apparent from the disclosures in the specification and the accompanying drawings.

This invention (in a preferred form) is illustrated in the drawings and hereinafter more fully described.

On the drawings:

Figure 1 is a perspective view of an improved ceiling hanger embodying the principles of this invention.

Figure 2 is a fragmentary sectional perspective view of a concrete floor or ceiling under construction illustrating the method of positioning the hangers and imbedding the same.

Figure 3 is an enlarged detail vertical section taken on line III—III of Figure 2 illustrating a ceiling hanger imbedded in a ceiling beam with the forms still in place.

Figure 4 is a fragmentary sectional perspective view of the concrete floor or ceiling with the form members removed and the portions of the hangers bent to afford a convenient support for ceiling bars.

Figure 5 is an enlarged fragmentary detail section taken on line V—V of Figure 4 illustrating the normal position of the lower portion of a hanger in dotted lines and the supporting position of the hanger in full lines.

Figure 6 is an enlarged fragmentary transverse section of a ceiling beam illustrating a modified form of positioning a ceiling hanger in place and means for tying a ceiling bar in position seated on the supporting flange of the hanger.

As shown on the drawings:

The improved ceiling hanger is preferably constructed of galvanized annealed sheet metal of any desired gauge and is of unitary construction adapted to be stamped from a sheet of metal and then bent into position for mounting. The improved hanger comprises a supporting plate 1, the side or longitudinal edges of which are provided with a plurality of notches 2 forming an irregular or toothed margin on each side of said supporting plate whereby the concrete may lodge or seat in the notches or recesses 2 when the hanger is mounted in place. Integrally formed at sub-

stantially right angles to the lower edge of the supporting plate 1 is an intermediate or bar receiving portion 3 having an opening or aperture 4 therein with one end thereof extending to the upper edge of a flange 5 integrally formed at substantially right angles on the outer edge of the intermediate hanger portion 3.

The improved ceiling hanger is adapted for use in an improved method for hanging or supporting ceilings from concrete floor and ceiling structures or the like. In a building construction when it is desired to construct a concrete floor from which a ceiling is to be hung a plurality of form beams 6 are first mounted in position upon any desired kind of supports and have supported transversely across the upper edges thereof a plurality of parallel beam form boards 7 upon which beam form metal pans or shells 8 are supported forming a plurality of parallel pockets or beam troughs. After the form members 7 and 8 have been mounted in proper relation upon the supporting framework or beams 6 the improved ceiling hangers may be set in spaced positions longitudinally within each of the beam troughs and upon the baseboards 7 forming part of the beam forms. To mount a ceiling hanger in place a slot 9 (Figure 3) is cut longitudinally in the upper face of the beam form board 7 to receive the hanger flange 5 seated therein with the intermediate plate 3 of the hanger seated flatly upon the upper face of the board 7, thus holding the hanger supporting plate 1 in substantially a vertical position projecting upwardly into the beam forming space provided above a form board 7 and between a pair of the metal shells 8. The improved ceiling hangers may thus be set in position at spaced intervals longitudinally along the beam form board 7. As illustrated in Figure 2 the hangers are placed on alternate form boards 7. The spacing arrangement of the ceiling hangers, however, is left to the contractor in charge of the job. After the hanger has been seated in place within a beam form concrete is poured over the form members 7 and 8 to form a concrete floor section 10 and a plurality of concrete ceiling beams 11 which may be reinforced if desired. It will thus be noted that with the concrete board in place the notched or toothed supporting plate 1 of a hanger is completely imbedded in the concrete with the concrete filling the notches 2 to rigidly hold a hanger in place, thereby obviating any danger of pulling the hanger out of the concrete beam after the concrete has properly set. After mounting a ceiling hanger in place, as described, and imbedding the same in concrete, the supporting beams 6 are removed after which the beam form planks or boards 7 and the metal forms 8 are pulled off leaving the flanged plates 8 of the ceiling hangers exposed, as

shown in dotted lines in Figure 5. The exposed plate 3 of each of the hangers is now released by any suitable means by engaging any suitable tool between the hanger plate 3 and the bottom face of a concrete beam. The 70 plate 3 is then bent from the dotted line position of Figure 5 into the plane of the hanger supporting plate 1, thereby positioning the flange 5 in a substantially horizontal position 75 parallel to the bottom face of the concrete beam in alignment with other ceiling hangers supported in adjacent or alternate ceiling beams. With the ceiling hangers arranged as illustrated in Figure 5 metal channel ceiling supporting beams or bars 12 are projected through the hanger openings 4 with the lower flanges of the channel beams resting on the flanges 5 of the hangers. The ceiling supporting arms or bars may thus be readily secured in place ready to have ceiling laths 85 tied or otherwise secured thereto to receive the plaster to form the ceiling.

If desired the improved ceiling hangers may be mounted with the supporting plates 1 of the hangers mounted transversely in the beam forms, as illustrated in Figure 6, in which event the flanges 5 of the hangers would be seated in transverse slots cut in the upper faces of the beam form boards 7. After the concrete has been poured in the 95 forms the forms may be removed and the hanger plates 3 bent downwardly into the planes of the supporting plate 1 and ceiling supporting channel bars 12 may then be seated upon the hanger flanges 5 and strapped 100 thereto by means of retaining wires or straps 13. It will be noted that the improved ceiling hangers may be mounted in position to permit the ceiling supporting channel bars to be either projected through the apertured 105 plates 3 and seated on the flanges 5 or may be placed parallel to the hanger plates 3 resting upon the flanges 5 and secured thereto by any suitable type of retaining means.

While an improved ceiling hanger has 110 been described constructed of sheet metal bent into a desired form, it will, of course, be understood that a hanger may be constructed of wire or other suitable materials and may be mounted in place similar to the arrangement described in connection with the illustrated hanger.

I am aware that many details of construction may furthermore be varied through a wide range without departing from the principles of this invention, and I therefore do not purpose limiting the patent granted hereon, otherwise than necessitated by the prior art.

I claim as my invention:

1. A unitary ceiling hanger constructed of sheet metal comprising a notched supporting plate, an apertured intermediate plate integrally formed thereon, and a flange on said apertured intermediate plate normally ex- 130

tending in a direction opposite to said supporting plate, said intermediate plate adapted to be bent into the plane of the supporting plate after the hanger has been mounted in place for use.

5 2. A ceiling hanger arranged to be embedded in concrete comprising a notched supporting member, a plate integrally formed at an angle thereon having an opening there-
in and adapted to be bent into the plane of said notched supporting member after the same has been imbedded in concrete, and a flange formed on said plate normally parallel to said supporting member adapted to afford a support for a ceiling bar projecting through said opening.

10 3. A unitary ceiling hanger comprising a sheet metal plate normally of Z shape and having an opening near one end thereof and a plurality of notches in the longitudinal margins of the opposite end thereof.

15 4. A ceiling hanger formed from a single sheet of metal, bent into substantially Z shape with the ends in substantially parallel planes and an intermediate portion substantially perpendicular thereto, and with one of the ends shorter than the other, said intermediate portion having an aperture therein adjacent and terminating at the shorter end portion.

20 5. A ceiling hanger formed from a single sheet of metal, bent into substantially Z shape with the ends in substantially parallel planes and an intermediate portion substantially perpendicular thereto, and with one of the ends shorter than the other, said intermediate portion having an aperture therein adjacent and terminating at the shorter end portion, said intermediate portion being bent into the plane of the longer end after the same has been secured in place for use and with the shorter end then lying in a plane perpendicular to the longer end for supporting a ceiling bar.

25 45 6. A ceiling hanger formed from a single sheet of metal, bent into substantially Z shape with the ends in substantially parallel planes and an intermediate portion substantially perpendicular thereto, and with one of the ends shorter than the other, said intermediate portion having an aperture therein adjacent and terminating at the shorter end portion, said intermediate portion being bent into the plane of the longer end after the same has been secured in place for use with the shorter end then lying in a plane perpendicular to the longer end for supporting a ceiling bar, said apertured intermediate portion arranged to receive and support a ceiling bar.

30 50 65 7. A ceiling hanger comprising a plate of sheet metal bent to provide a supporting portion, an intermediate portion substantially perpendicular to the supporting portion, and a flange portion at the other end of said in-

termediate portion, said flange and said supporting portion being in parallel planes and extending in opposite directions from said intermediate portion, said intermediate portion having an aperture therein for the reception of a ceiling bar when said hanger is supported in place for use and said intermediate portion is bent into the plane of said supporting portion.

70 75 In testimony whereof I have hereunto subscribed my name.

EUGENE T. McCARTY.
